ATTORNEY

UNITED STATES PATENT OFFICE.

GEORGE M. STRATTON, OF NEW BRUNSWICK, NEW JERSEY.

LIGATURE-HOLDER.

1,103,227.

Specification of Letters Patent.

Patented July 14, 1914.

Application filed August 30, 1913. Serial No. 787,451.

To all whom it may concern:

Be it known that I, GEORGE M. STRATTON, a citizen of the United States, and a resident of New Brunswick, in the county of 5 Middlesex, State of New Jersey, have invented certain new and useful Improvements in Ligature-Holders, of which the following is a specification, reference being had to the accompanying drawing.

10 My invention principally relates to holders for surgical and other ligatures, and particularly to that style wherein ligatures are wound upon bobbins or spools within a sealed container, filled with an antiseptic 15 fluid, from which receptacle the ligatures may be withdrawn as desired.

Among the principal objects of my invention are to provide a ligature holder of simple and durable form, which may be 20 readily and cheaply constructed, and within which the bobbins or spools upon which the ligatures are wound may be assembled with a minimum outlay of time and expense, and which shall reduce the liability of breakage 25 of the various parts in assembling.

My invention further includes all of the other various novel features and objects hereinafter more definitely specified.

In the accompanying drawing, Figure 1 30 is a central vertical section of a ligature holder, constructed in accordance with the principles of my invention, a portion thereof being shown in elevation for the sake of clearness; Fig. 2 is a transverse horizontal section taken upon the line 2—2 in Fig. 1; Fig. 3 is a central vertical section, also 35 partly in elevation, of a slightly modified form of the device; and Fig. 4 is a transverse horizontal section taken on line 4—4 of Fig. 3.

Referring to the drawing, one form of my invention therein illustrated in Figs. 1 and 2 consists in a bottle 1, preferably formed of glass, or other suitable material, 45 the exterior of which may be of cylindrical form. The upper end of the bottle may be provided with threads 2 upon its exterior, suitable for the reception of an internally threaded metallic cap 3 which serves as a 50 closure for the upper end of the bottle. The interior of the bottle may preferably be formed slightly elliptical in section as clearly shown in Fig. 2, and with a plurality of steps or shoulders 5, 6, 7. For this 55 latter purpose, therefore, the bottle may be

constructed with several different internal diameters, being of maximum internal diameter at the top, and of minimum internal diameter at the bottom, as clearly shown in Fig. 1. Furthermore, it may be found desirable to form the interior of the bottle with a slight taper from top to bottom for the purpose of permitting the ready withdrawal of the plunger used in forming the bottle when the same is being molded. It 60 will be understood, of course, that the bottle may be constructed with as many steps or shoulders 5, 6, 7 as may be desired, but in practice the bottles are usually formed with three shoulders as illustrated in Fig. 70

1. For the purpose of holding the ligatures 8, which may be either of graduated sizes or all of the same size, a plurality of spools 10 are provided, each having a suitable central cylindrical opening adapted for the reception of the pivot rods 12, 13, 14. These rods are graduated in length, so as to fit snugly between the walls of the interior of the bottle when resting upon the shoulders 5, 6, and 7 as clearly shown in Fig. 1. In 80 other words, the rod 12 is of such a length as to fit snugly between that portion of the walls of the bottle directly above the shoulder 5 when approximately parallel to the major axis of the ellipse formed by the interior of the bottle at that point; and the rod 13 is adapted to fit above the shoulder 6 in like manner, as is the rod 14 above the shoulder 7. Resting upon the upper side of the rod 14, and preferably of such a height 85 as to contact with the underside of the pivot rod 13 is a cylindrical separator 20, which may preferably be formed of glass or other suitable material, and in like manner above the pivot rods 13 and 12 are located similar 90 separators 21 and 22. A stopper 24, of rubber or other suitable material may be inserted in the mouth of the bottle, and rests against the upper end of the separator 22. These separators serve to prevent the pivot 95 rods from being displaced when the ligatures 8 are withdrawn from the bottle, and they may preferably be formed in different sizes as regards their diameters, so that each may fit loosely within that portion of the 100 interior of the bottle in which it is designed to be positioned, its external diameter being approximately that of the smaller diameter of the bottle at that point. The separator 22 will thus be of greater diam- 110

eter than the separator 21, which in turn will be of greater diameter than the separator 20, in order that each may be properly positioned within the bottle.

5 In Figs. 3 and 4 is shown a slightly modified form of my invention in which the steps or shoulders 5, 6, and 7 in the interior of the bottle have been omitted, the bottle being merely formed with a slight interior 10 taper from top to bottom. In this form of construction, the pivot rods 31, 32 and 33 are formed in graduated lengths as previously described in connection with the form of my invention illustrated in Figs. 1 and 15 2, but it is necessary to make use of an additional separator, which rests upon the bottom of the bottle beneath the lowermost pivot rod 33, in order to provide a support for the latter. The other separators 36, 37 20 and 38 are located between the several pivot rods, and the upper separator 38 contacts with the underside of the stopper 24 in a manner similar to that previously described.

In assembling the various parts, the ligatures, having been wound upon spools 10, the lowermost spool with its pivot rod positioned therein is inserted in the bottle in such a manner that the pivot rod will rest upon the upper face of the shoulder 7, or, 25 upon the separator 35, as the case may be, and a separator of the proper size being placed above the pivot rod, the next spool upon its pivot is introduced within the bottle, and so on until all the spools with their 30 pivots and all the separators have been introduced, in which position, owing to the several pivot rods being of approximately the length of the major axes of the various elliptical sections of the bottle, the several 35 pivot rods will be constrained to lie in substantially the same vertical plane. The bottle may then be filled with an antiseptic liquid; the ligatures threaded through proper perforations in the stopper 24, and 40 the latter inserted in the mouth of the bottle so that its under side contacts with the edge of the uppermost separator, after which cover 3 may be screwed in place. When it is desired to make use of the ligatures, the cap 3 is removed, and one or more 45 of the ligatures withdrawn through the stopper 24, the spools 10 rotating meanwhile upon the pivot rods, which latter are held in place vertically by the separators, and 50 horizontally by the elliptical formation of the interior of the bottle.

I do not desire to limit myself to the precise details of construction or arrangement of that form of my invention herein described, as it will be evident that various changes and modifications may be readily made therein, without departing from the spirit and scope of my invention as defined in the appended claims.

55 Having thus described my invention, what

I claim and desire to protect by Letters Patent of the United States is:

1. A holder for ligatures, or the like, comprising a bottle having its interior elliptical in cross section, a plurality of spools maintained in spaced relation within said bottle and a plurality of separate, relatively short tubes between said spools. 70

2. A holder for ligatures, or the like, comprising a bottle having an interior of elliptical cross section, and formed with a plurality of horizontal shoulders, straight pivot rods of graduated length resting upon said shoulders, and spools rotatable upon said rods. 75

3. A holder for ligatures, or the like, comprising a bottle having its interior of elliptical cross section and formed with a plurality of shoulders upon its interior face, a plurality of straight pivot rods of uniform diameter and of different lengths adapted to fit snugly within said bottle upon said shoulders, spools rotatable upon said pivot rods, and separate spacing means comprising a plurality of rings of varying diameter between said rods operative to hold said rods in spaced vertical relation. 85

4. A holder for ligatures, or the like, comprising a bottle having its interior of elliptical cross section, and formed with a plurality of horizontal shoulders, straight pivot rods graduated in length adapted to rest upon said shoulders and to fit snugly within said bottle, and spacing means comprising a plurality of unconnected cylindrical rings between said rods operative to maintain said rods in spaced vertical relation. 95

5. In a holder for ligatures or the like, the combination of a bottle having a plurality of different internal diameters, the cross section of the interior of said bottle being in the form of an ellipse, and a plurality of straight pivot rods of uniform diameter and of graduated lengths maintained in vertically spaced relation within said bottle, the length of any given pivot rod being approximately equal to the greatest diameter of the cross section of the bottle adjacent such rod. 105

6. A holder for ligatures, or the like, comprising a bottle having a plurality of shoulders formed therein, straight pivot rods horizontally supported upon said shoulders, and a plurality of unconnected tubular spacing means between said rods operative to maintain said rods in spaced vertical relation. 115

7. In a holder for ligatures or the like, the combination of a bottle having a plurality of shoulders formed therein, the interior of said bottle being elliptical in cross section, a plurality of straight pivot rods of graduated length horizontally supported at their ends upon said shoulders, and spacing means comprising a plurality of relatively 125

short cylindrical tubes between said rods, operative to maintain said rods in spaced vertical relation, the length of any given pivot rod being approximately equal to the 5 major axis of the cross section of the bottle adjacent such rod, whereby all of said rods are maintained in substantially the same vertical plane.

8. In a holder for ligatures or the like, the 10 combination of a bottle having a plurality of horizontal shoulders formed upon its inner side, a plurality of straight pivot rods of constant diameter resting upon said shoulders, spools rotatable upon said rods, 15 a plurality of independent relatively short cylindrical spacing rings interposed between said rods whereby said rods are maintained in spaced vertical relation, and a stopper in contact with the uppermost of said rings.

20 9. A holder for ligatures, or the like, com-

prising a bottle having a plurality of horizontal shoulders upon its inner wall, straight pivot rods supported at their ends upon said shoulders, spools rotatable upon said rods, a stopper in the mouth of said bottle, 25 and a plurality of unconnected cylindrical spacing rings between said rods, the interior of said bottle being of elliptical cross section, the length of any given rod being substantially equal to the length of the major axis of such cross section adjacent such rod.

In witness whereof, I have hereunto set my hand this 27th day of August, A. D. 1913.

GEORGE M. STRATTON.
